SEAMING MECHANISM

Willy Diezel, Fairfield, Conn., assignor to The Max Ams Machine Company, Bridgeport, Conn., a corporation of Connecticut

Application December 23, 1943, Serial No. 515,401

1 Claim. (Cl. 113—24)

The present invention relates to seaming machines, whether of the type that merely crimps or curls sheet material parts, or of the type that performs a double-seaming operation.

The main object of the invention is to provide a seaming mechanism of simple construction that will unite heavy gauge sheet material members without throwing an undue load on the actuating parts of the device.

Figs. 1 to 5 inclusive show one form of the invention as applied to a crimping machine;

Fig. 1 is a fragmentary view in side elevation of so much of a crimping machine as is necessary to an understanding of the invention;

Fig. 2 is a horizontal sectional view substantially on the plane of line 2—2 of Fig. 1;

Fig. 3 is a vertical sectional view substantially on the plane of line 3—3 of Fig. 2;

Fig. 4 is a horizontal sectional view substantially on the plane of line 4—4 of Fig. 3;

Fig. 5 is a vertical sectional view substantially on the plane of line 5—5 of Fig. 3;

Figs. 6 to 14 inclusive show another form of the invention as applied to a double seaming machine;

Fig. 6 is a fragmentary view in side elevation of so much of a double seaming machine as is necessary to an understanding of the invention;

Fig. 7 is a horizontal sectional view substantially on the plane of line 7—7 of Fig. 6;

Fig. 8 is a vertical sectional view substantially on the plane of line 8—8 of Fig. 9, showing the details associated with the first-operation seaming rollers;

Fig. 9 is a vertical sectional view substantially on the plane of line 9—9 of Fig. 8;

Fig. 10 is a horizontal sectional view substantially on the plane of line 10—10 of Fig. 8;

Fig. 11 is a horizontal sectional view substantially on the plane of line 11—11 of Fig. 8;

Fig. 12 is a vertical sectional view substantially on the plane of line 12—12 of Fig. 13, showing the details associated with the second-operation seaming rollers;

Fig. 13 is a vertical sectional view substantially on the plane of line 13—13 of Fig. 14; and

Fig. 14 is a horizontal sectional view substantially on the plane of line 14—14 of Fig. 12.

Attention is first directed to that form of the invention which is disclosed in Figs. 1 to 5 inclusive, which figures show that form of seaming mechanism commonly referred to as a crimping mechanism. In the present instance, the work-piece (Fig. 3) is a container 15 to which a con-

tainer-end 16 has been double-seamed and to which it is desired to attach an extra cover 17 by means of a crimping or curling operation, and the mechanism disclosed has for its purpose the crimping of this extra cover, 17, to parts 15 and 16 that have been previously united.

18 is a supporting member provided with a seamer head 19 carrying the crimping rollers to be presently described. In accordance with well-understood practice, either the work-piece or the seamer head may rotate but, in the present instance, the work-piece stands still and the supporting member and seamer head rotate. Accordingly, 20 is a non-rotating shaft to which 15 chuck 21 is attached, whereas supporting member 18, and thereby seamer head 19, is rotated by gear 22.

The seaming rollers, here in the form of crimping rollers 23, may vary in number but, in the 20 present instance, it is preferred to employ three such rollers with means for simultaneously moving them toward and away from the work-piece. As indicated particularly in Fig. 2, the means for effecting this in-and-out movement of the three 25 crimping rollers are alike, and it will therefore only be necessary to describe one of these means.

24 is a seaming-roller carrier mounted to slide substantially radially in the seamer head, and 25 is a subsidiary carrier, on which roller 23 is 30 rotatably mounted, said subsidiary carrier 25 being slidably adjustable on 24 by means of threaded stem 26 mounted to rotate, but not to move endwise, in bridge-portion 27 of 24. It will be understood that rotation of stem 26 in bridge-portion 27 will cause an adjustment of subsidiary carrier 25 in one direction or the other, depending upon the direction of rotation of stem 26. 28 and 29 indicate two complementary fulcra-members, one, 28, being pivotally supported in bearings 30 on seamer head 19, and, the other, 29, being pivotally supported in suitable 35 bearings 31 on seaming-roller carrier 24. 32 and 33 denote toggle-links that are pivotally connected at 34 and which are interposed between 40 said fulcra-members. It will be seen that, when 45 said toggle-links are straightened, seaming-roller carrier 24 will be moved toward the work-piece and that, when said toggle-links are flexed, seaming-roller carrier 24 will be moved away from the 50 work-piece. 35 is a sleeve mounted to slide lengthwise of, and to rotate with, supporting member 18, as by means of one or more keys 36. Suitable connecting means are provided to 55 straighten and flex said toggle-links in response to the sliding movement of sleeve 35. In the

present instance, 37 indicates an arm rigidly connected to toggle-link 33, and it will be seen that 37 and 33 constitute, in effect, an elbow or bell-crank; and 38 is a link pivotally supported at 39 on said sleeve 35 and pivotally connected at 40 to said arm 37. It will now be apparent (Fig. 3) that an upward movement of sleeve 35 will straighten the toggle-links and that a downward movement will flex them. 41 is a cam shaft making one revolution to a plurality of revolutions, such as four, of sleeve 35. Mounted to rotate with said cam shaft, 41, is a cam 42. Pivotally mounted at 43 in the framework is a cam lever 44 having a cam roll 45 to engage said cam, and, connected to said cam lever, is a bifurcated lever 46 having rollers 47 (only one of which is shown) to engage grooved collar 48 of sleeve 35 to raise and lower the latter in response to rotation of cam 42 during each revolution of said cam.

It will be seen from the foregoing that, when seaming or crimping roller 23 begins to act on the work-piece, toggle-links 32 and 33 are approaching their straightened position and that, at the moment of greatest strain, the toggle-links are straightened. This means that, as the seaming or crimping pressure is increased, the operating pressure at cam 42 and on collar 48 is at its lowest. It will further be seen that the construction of the mechanism is extremely simple and, also, that the necessity for differential gearing is avoided, in that a simple train of gears as 49 can be employed to transmit motion both to supporting member 18 and cam shaft 41.

Attention is now directed to Figs. 6 to 14 which disclose seaming mechanism of the double-seaming type. In this form of the invention, supporting member 50 and seamer head 51 rotate and shaft 52 and chuck 53 are non-rotatable. Seamer head 51 is provided with two first-operation seaming-roller carriers, one of which is shown in detail in Figs. 8 to 11, and two second-operation seaming-roller carriers, one of which is shown in detail in Figs. 12 to 14. The assembly of both seaming-roller carriers is shown in Figs. 6 and 7. As all the seaming-roller carriers, and the elements associated therewith, are substantially alike, one general description will suffice for all, and any differences that exist will be subsequently pointed out.

Reference character 54 indicates a seaming-roller carrier mounted to slide substantially radially in the seamer head. 55 is a subsidiary carrier, on which, as the case may be, a first-operation seaming roller 56 or a second-operation seaming roller 56a is rotatably mounted. Subsidiary carrier 55 is slidably adjustable on 54 by means of threaded stem 57 mounted to rotate, but not to move endwise, in bridge-portion 58 of 54. It will be understood that rotation of stem 57 in bridge-portion 58 will cause an adjustment of subsidiary carrier 55 in one direction or the other, depending upon direction of rotation of stem 57. 59 and 60 indicate two complementary fulcra-members, one, 59, being pivotally supported in bearings 61 of the seamer head, and, the other, 60, being pivotally supported in suitable bearings 62 on seaming-roller carrier 54. 63 and 64 denote toggle-links that are pivotally connected at 65 and which are interposed between said fulcra-members. It will be seen that, when said toggle-links are straightened, seaming-roller carrier 54 will be moved toward the work-piece, and that, when said

toggle-links are flexed, seaming-roller carrier 54 will be moved away from the work-piece.

The means for straightening and flexing the toggle-links are as follows: 66 and 67 indicate two sleeves mounted to slide lengthwise of and to rotate with supporting member 50. In the present instance, sleeve 67 is slidably keyed directly to supporting member 50 as by one or more keys 68, and sleeve 66 is slidably keyed to sleeve 67 as by means of one or more keys 69. 70 is a cam shaft making one revolution to a plurality of revolutions, eight for instance, of supporting member 50. 71 and 72 indicate two cams mounted to rotate with shaft 70. Pivotally supported on the framework at 73 and 74 are two cam levers 75 and 76, each of which carries a cam roller 77 or 78 to engage cams 71 and 72 respectively. Cam lever 75 carries a bifurcated portion 79 to engage collar or grooved member 80 of sleeve 66, and cam lever 76 similarly carries a bifurcated portion 81 to engage collar or grooved member 82. Cams 71 and 72, during each revolution of shaft 70, effect a sliding movement in opposite directions of sleeves 66 and 67 and, owing to the timing of said cams, the movements of the two sleeves are independent of one another.

The sliding movements of sleeves 66 and 67 are utilized to straighten and flex toggle-links 63 and 64. Sleeve 66 is provided with two links 83 pivoted at 84, each of which links is pivotally connected at the pivotal joint, 65, between toggle-links 63 and 64 of a first-operation seaming-roller carrier. Similarly, sleeve 67 is provided with two links 85 pivoted at 86, each of which links is pivotally connected at the pivotal joint, 65, between toggle-links 63 and 64 of a second-operation seaming-roller carrier.

It will now be understood that, when sleeve 66 is moved downward (as in Fig. 8), the toggle-links of the first-operation seaming-roller carriers will be straightened, thereby causing first-operation seaming rollers to engage the work-piece, and that, when said sleeve 66 moves upward, said toggle-links will be flexed and the first-operation seaming rollers will recede from the work-piece. Likewise, when sleeve 67 descends (as in Fig. 12), the toggle-links of the second-operation seaming-roller carriers will be straightened, thereby causing second-operation seaming rollers to engage the work-piece, and that, when said sleeve 67 moves upward, said toggle-links will be flexed and the second-operation seaming rollers will recede from the work-piece.

In order to permit the second-operation seaming rollers to pass over a high spot on the work-piece, bearings 61 are made slightly yielding by having their brackets 87 mounted on posts 88, openings 89, through which posts 88 pass, being slightly larger (Fig. 14) than the diameter of said posts. Springs 90 surround pins 91, carried by brackets 87, and interposed between stationary bearing members 92, on the seamer head, and bolts 93 on pins 91.

I claim:

In a seaming mechanism having a seaming-roller carrier that has a straight-line movement toward and away from the work-piece to be acted upon, and having power-actuated operating means to effect such movement: a supporting-member constructed and arranged to rigidly support a seamer head extending at right angles to said supporting-member, and to support a sleeve slidably lengthwise of said supporting-member;

a seamer head, rigidly carried by said supporting-member and extending at right angles thereto, said seamer head having a radial guideway to slidably receive a seaming-roller carrier, and constructed and arranged to be connected to said seaming-roller carrier by means of toggle-links; a seaming-roller carrier, having provision to support a seaming roller, constructed and arranged to slide in the radial guideway of said seamer head and to be connected to said seamer head by means of toggle-links; a seaming roller supported by said seaming-roller carrier to follow the radial sliding movement of the latter in a straight line toward and away from the work-piece to be acted upon; means to effect radial movements of said seaming-roller carrier, toward and away from the work-piece to be acted upon, in response to the action of the power-actuated operating means and to protect said power-actuated operating means against excessive strain during that movement of said seaming-roller carrier which brings said seaming roller into engagement with the work-piece being acted upon, including: two toggle-links constructed and arranged to extend radially of said seamer head and to be completely straightened in moving said seaming-roller carrier toward the work-piece, one of said toggle-links having a pivotal support on said seamer head and the other of said toggle-links having

5 a pivotal support on said seaming-roller carrier, and said toggle-links having pivotal connection at a point equidistant from their pivotal supports on said seamer head and said seaming-roller carrier; a sleeve constructed and arranged to slide on said supporting-member and to be rigidly connected to and follow the movement of a grooved collar forming part of power-actuated operating means; power-actuated operating means constructed and arranged to impart a sliding movement to said sleeve of such predetermined amplitude as to flex said toggles when said seaming-roller carrier is moving away from the work-piece, and to completely straighten said toggles 10 when said seaming-roller carrier is moved toward the work-piece, said power-actuated operating means including a grooved collar, connected to slide with said sleeve, and a pivotally supported oscillatory actuating lever having means to engage said grooved collar to effect sliding movement thereof and of said sleeve; and a connecting means between said sleeve and said toggle-links to transmit the sliding movement of said collar and sleeve to flex said toggles when said 15 seaming-roller carrier is moving away from the work-piece, and to completely straighten said toggles when said seaming-roller carrier is moved toward the work-piece.
